UNITED STATES PATENT OFFICE.

ARTHUR GIESLER, OF DAYTON, OHIO, ASSIGNOR TO THE STILWELL-BIERCE & SMITH-VAILE CO., OF DAYTON, OHIO, A CORPORATION OF NEW JERSEY.

TURBINE-WATER-WHEEL SYSTEM.

SPECIFICATION forming part of Letters Patent No. 705,994, dated July 29, 1902.

Application filed September 27, 1900. Serial No. 31,243. (No model.)

To all whom it may concern:

Be it known that I, ARTHUR GIESLER, a citizen of the United States, residing at Dayton, in the county of Montgomery and State 5 of Ohio, have invented certain new and useful Improvements in Turbine-Water-Wheel Systems; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to improvements in water-wheel systems and possesses the novel and advantageous features hereinafter described and claimed.

In my pending application, Serial No. 20 31,689, filed October 1, 1900, I have claimed, broadly, means for admitting air in the wheel-casing for the purpose of maintaining the water therein at a proper level. The present invention appertains more specifically to one 25 form of means for actuating the valve through which said air is admitted.

Experience in connection with the manufacture and installation of turbine water-wheels has demonstrated that in very many 30 instances owing to the physical conditions it is desirable and in many cases necessary to place said turbines a considerable distance above the water in the tail-race. In order to do this without loss of head and consequent 35 loss of power, it becomes necessary to connect the turbine with the water in the tail-race by means of a draft-tube, which may vary in length according to requirements. With certain types of water-wheels—to wit, 40 those known as the "Girard" or "impulse" type—my experience has demonstrated the desirability of maintaining the height of the water in the draft-tube at a predetermined level and that this can be best accomplished 45 by the admission of air to the draft-tube. The quantity of air required for that purpose depends upon the quantity of water the wheel is discharging, which will depend upon the stage of opening of the water-wheel gate,

which in turn depends upon the load the 50 water-wheel is carrying—*i.e.*, in practice the water-wheel gate is controlled by a governor or regulator, which opens or closes it to accommodate the varying load on the wheel. The height of water in the draft-tube having 55 been determined at a point where the water-wheel will develop its greatest efficiency, it is evident that an automatic device for maintaining that level under varying loads becomes a great desideratum. This result is 60 accomplished by my invention, which I will now proceed to describe.

Referring to the annexed drawings, Figure 1 is a sectional elevation of a water-wheel system constructed in accordance with my 65 invention. Fig. 2 is an enlarged sectional elevation of the air-valve. Fig. 3 is a similar elevation of the inner casing or bushing of the air-valve as shown in Fig. 2. Fig. 4 is a top view of the valve-plug. 70

In the specification similar letters of reference indicate corresponding parts.

A designates a turbine-wheel casing, which is connected with the tail-race by a draft-tube B, said draft-tube being of suitable length to 75 extend from said wheel-casing to the tail-water. Within said casing there is horizontally mounted one or more turbine wheels C in the usual manner, said turbines being of the impulsi or Girard type. 80

N N designate two deflector-plates, which project from the interior walls of the turbine-casing. These plates extend throughout the length of the casing and occupy inclined positions, as shown in Fig. 1 of the drawings. 85 The said plates provide an inclosure above the turbine wheel, from which the air is admitted directly to the wheel-buckets as the wheel rotates.

D designates a water-cylinder placed in 90 suitable proximity to the wheel-casing and connected therewith by a water-tube E. Within said water-cylinder there is placed a float F, the position of which is at all times controlled by the water-level within the wheel-casing. This float is connected to a hollow stem G, which has a valve-plug H connected to its upper end. 95

I designates a cylinder or valve casing, the sides of which are provided with a suitable number of air-ports I'. This valve-casing I is mounted on the upper end of a hollow extension D', extending from the float-cylinder D, said extension inclosing the float-stem G. The air-valve is connected with the wheel-casing by means of a T-fitting and a pipe K, which discharges into the wheel-casing at predetermined periods, as will hereinafter appear. The plates N N provide a compartment or space for the air which enters through pipe K.

I" designates an inner sleeve or bushing which is placed on the interior of the valve-casing I. The said bushing is also provided with a suitable number of ports J, which correspond in shape with the air-ports I' in the casing I, and when the said bushing is in proper position within the casing I the openings or ports J therein will register with the ports I'. The valve-plug H being attached to the stem G, a connection is formed between said valve-plug and the float F. It will therefore be seen that the movements of the float, which are due to the rise and fall of the water in the draft-tube, will be transmitted to the valve-plug H, and this will accordingly cover or uncover the air-ports I' to exclude or admit air to the wheel-casing. The valve-plug H thus automatically covers and uncovers the air-ports I'. When the valve-plug H is in such position as to close said ports altogether, atmospheric pressure is entirely excluded from the valve. This position of the valve will take place when the water within the wheel-casing is maintained at the desired level, which is substantially as shown in Fig. 1. When the water within the wheel-casing rises above the desired level, a corresponding rise takes place in the float-chamber D, and the float F, which is carried upon the surface of the water within the chamber D, will rise therewith, and the valve-plug H will also be moved to uncover the valve-ports I'. Air will be then admitted through the valve in and through the passage K to the interior of the wheel-casing, as shown by the various arrows. Air thus entering the wheel-casing will exert the necessary pressure upon the surface of the water within said casing, and the water will be maintained at the desired level. The wheel-casing and the adja-

cent float-chamber are exhausted of air by the water entering the wheel-casing and issuing through the radial discharging turbine water-wheel. The air is exhausted or rarefied to an extent that is due to the height from the tail-water to the predetermined point of water within the turbine-casing. For example, the distance between the predetermined point of the tail-water is, say, ten feet. It follows, therefore, that a correct vacuum-gage should register about nine inches of vacuum.

It will be understood that a connection between the float-chamber D and the tail-water may be made at any point between the level of the water in the wheel-casing and the tail-water.

Having described my invention, I claim—

1. In a horizontal-water-wheel system, the combination of a turbine-casing, a horizontal turbine wheel mounted in said casing, said turbine wheel being of the impulse or Girard type, a draft-tube connecting said casing with the tail-water, an auxiliary water-chamber, a communication between the draft-tube or wheel-casing and said auxiliary water-chamber, a float within said auxiliary water-chamber, an air-valve controlled by said float, and a communication between said air-valve and the turbine-casing whereby air is discharged into said turbine-casing above the surface of the water, substantially as and for the purposes specified.

2. In a horizontal-water-wheel system, the combination of a turbine-casing, a horizontal turbine wheel mounted in said casing, said turbine being of the impulse or Girard type, a draft-tube connecting said casing with the tail-water, an auxiliary water-chamber, a passage between the draft-tube or wheel-casing and said auxiliary water-chamber, a float within said auxiliary water-chamber, an air-valve carried by said float, and a communication between said air-valve and said turbine-casing whereby air is discharged to said turbine-casing above the turbine wheel, substantially as and for the purposes specified.

In testimony whereof I affix my signature in presence of two witnesses.

ARTHUR GIESLER.
